UNITED STATES PATENT OFFICE.

CLARENCE A. BUSKIRK, OF ST. LOUIS, MISSOURI.

CONCRETE BLOCK.

952,305.

Specification of Letters Patent. Patented Mar. 15, 1910.

Application filed June 2, 1909. Serial No. 499,642.

To all whom it may concern:

Be it known that I, CLARENCE A. BUSKIRK, citizen of the United States, residing at St. Louis, in the State of Missouri, have 5 invented certain new and useful Improvements in Concrete Blocks, of which the following is a specification.

This invention relates to artificial stone, bricks or blocks, and has for its object to 10 provide a brick or block formed of mating sections connected by tie plates so that when the blocks are laid into a wall, the latter will be formed with a vertical air chamber or flue, thus to prevent moisture on the outer 15 face of the wall from penetrating the blocks and wetting or otherwise injuring the plaster.

A further object of the invention is to provide means for maintaining the block or 20 brick sections in proper spaced relation, and means for centering the blocks or bricks in one course with respect to the blocks or bricks in an adjacent course.

A further object is to insure proper bonding of the blocks by forming the tie plates 25 with perforations adapted to receive vertical pins or studs, which latter are positioned in suitable recesses in the blocks when laid into a wall.

30 A still further object of the invention is generally to improve this class of devices so as to increase their utility, durability and efficiency.

Further objects and advantages will appear in the following description, it being understood that various changes in form, proportions, and minor details of construction may be resorted to within the scope of the appended claims.

40 For a full understanding of the invention and the merits thereof and also to acquire a knowledge of the details of construction and the means for effecting the result, reference is to be had to the following description 45 and accompanying drawings, in which:

Figure 1 is a perspective view of a portion of a wall formed of artificial stone, bricks or blocks constructed in accordance with my invention; Fig. 2 is a perspective view of one 50 of the bricks or blocks detached; Fig. 3 is a vertical sectional view of the wall; Fig. 4 is a top plan view of the wall illustrating a slightly different form of the invention. Fig. 5 is a detail perspective view of the tie

plate detached; Fig. 6 is a similar view of 55 the spacing block detached.

Corresponding and like parts are referred to in the following description and indicated in all the views of the drawings by the same reference characters.

The brick or block forming the subject matter of the present invention comprises mating sections 5 and 6, each preferably rectangular in shape as shown, and formed of cement, concrete, terra-cotta, or other suitable material. The front section 6 is preferably of less width than the rear section 5 and may be molded or otherwise formed with an ornamental face in imitation of cut or chipped rock so as to impart an attractive 70 appearance to the wall, and in some cases this front section may be formed of clay and the rear section of concrete.

Formed in the upper and lower longitudinal edges of the block sections 5 and 6, are 75 seating recesses 7 and communicating with said seating recesses are shallow depressions 8 for the reception of tie plates 9. The recesses 7 are positioned near the inner faces of the block sections, while the depressions 8 80 extend through said inner faces. The tie plates 9 are preferably formed of flat strips of zinc or other suitable material, the opposite ends of which are perforated at 10 for registration with the adjacent recesses 7 to 85 permit the insertion of bonding members or pins 11. The rear walls of the depressions 8 terminate short of the outer faces of the block sections so that when the tie plates 9 are positioned in said depressions and the 90 blocks laid into a wall, said tie plates will be entirely concealed. The tie plates 9 serve to maintain the block sections 5 and 6 in spaced parallel relation to form an intermediate air chamber or compartment 13 so that 95 when the blocks or bricks are laid into a wall, the latter will be formed with a vertical air chamber or flue extending the entire height of the wall thus to permit the circulation of air throughout the entire height 100 and length of the wall, and prevent moisture deposited on the outer faces of the bricks or blocks from penetrating the wall and wetting or otherwise injuring the plaster on the inner face of said wall.

In order to insure the proper spaced relation of the bricks or blocks, some of the tie plates are formed with spacing members or blocks 14 prefer-

ably secured to the intermediate portions of said tie plates by screws or similar fastening devices and which bear against the inner faces of the block sections, as best shown 5 in Fig. 2 of the drawings.

In constructing a wall, the bricks or blocks are laid in superposed courses with the bricks or blocks of the several courses arranged to break joint. After the first 10 course of the wall is laid, the bonding pins 11 are positioned in the recesses 7 and the perforated ends of the tie plates 9 passed over the adjacent ends of the bonding pins 11 and forced downwardly within the seating 15 depressions 8. The bricks or blocks of the next succeeding course are then positioned on the blocks of the previously laid course with the recesses 7 in registration with the projecting ends of the bonding pins 20 11, it being of course, understood that prior to laying the second course of bricks or blocks the usual layer of mortar will be spread thereon. The block sections forming the side walls of a building are preferably 25 laid opposite each other with their end portions in alinement, while the bricks or blocks at the corners of the wall, are disposed one slightly in advance of the other, as best shown in Fig. 3 of the drawings, so 30 as to permit the formation of said corners without the necessity of breaking or otherwise mutilating the blocks.

By forming the upper and lower longitudinal edges of the block sections with the 35 depressions 8, any number of tie plates 9 may be positioned in said depressions in order to reinforce and strengthen the wall. By making the blocks or bricks in separate sections and bonding said sections after the same 40 have been laid into a wall, the construction of the wall is materially facilitated, while by spacing said sections apart in the manner set forth, the formation of mold or moisture on the inner face of the wall is effectually 45 prevented.

It will, of course, be understood that the bricks or blocks may be made in different sizes and shapes and formed of cement, terra-cotta, or other material found suitable 50 or desirable for this purpose.

Having thus described the invention, what is claimed as new is:

1. A wall formed of a plurality of blocks laid in superposed courses and arranged to 55 break joint, said blocks being each formed of mating sections having their upper and lower longitudinal edges provided with spaced seating recesses, there being transverse 60 depressions formed in the block sections at said recesses and opening at the inner faces thereof, flat tie plates seated in said depressions and having their exposed faces disposed flush with the adjacent longitudinal edges of the block and pierced by

openings registering with the adjacent recesses, and bonding pins seated in the recesses in the mating sections of the blocks in one course of the wall, and extending through the perforations in the tie plates for engagement with the recesses in the block 70 sections of an adjacent course. 65

2. A wall formed of a plurality of blocks laid in superposed courses and arranged to break joint, said block being each formed of mating sections of the same height but of 75 different widths having their upper and lower longitudinal edges formed with seating recesses and provided with transverse depressions communicating with said seating 80 recesses and opening through the inner faces of the block sections, the outer walls of the depressions being spaced from the exposed faces of the block sections to form stop shoulders, flat tie plates connecting the several block sections and having their outer 85 ends bearing against said stop shoulders and provided with perforations adapted to register with the recesses in the adjacent block sections and their intermediate portions provided with depending spacing 90 blocks adapted to bear against the inner faces of said block sections, and pins seated in the recesses in the mating sections of the blocks in one course of the wall and projecting through the perforations in the tie 95 plates for engagement with the seating recesses in the block sections of an adjacent course. 95

3. An artificial stone block comprising substantially rectangular mating sections of 100 the same length and height but of different thickness and having their upper and lower longitudinal edges formed with seating recesses, there being transverse depressions formed in the longitudinal edges of the 105 block sections at said recesses and having their outer ends spaced from the outer faces of the block sections and their inner ends opening through the inner faces of the block sections, flat tie plates seated in the depressions and disposed flush with the adjacent longitudinal edges of the block sections, said tie plates having perforations formed therein and registering with the seating recesses in said block sections, pins extending 110 through the perforations in the plates and seated in the adjacent recesses, and spacing blocks depending from the intermediate portions of the tie plates and adapted to bear against the inner faces of the block sections, 115 thereby to maintain the latter in spaced relation to each other. 120

In testimony whereof I affix my signature in presence of two witnesses.
